UNITED STATES PATENT OFFICE.

LOUIS S. BURBANK, OF LUDLOW, MASSACHUSETTS, ASSIGNOR TO LUDLOW MANUFACTURING ASSOCIATES.

AUTOMATIC FILLING-CHANGING LOOM.

1,294,871.

Specification of Letters Patent. Patented Feb. 18, 1919.

Application filed February 26, 1917. Serial No. 150,874.

To all whom it may concern:

Be it known that I, LOUIS S. BURBANK, a citizen of the United States, and a resident of Ludlow, in the county of Hampden and State of Massachusetts, have invented an Improvement in Automatic Filling-Changing Looms, of which the following description, in connection with the accompanying drawings, is a specification, like characters on the drawings representing like parts.

This invention relates to looms and particularly to automatic filling changing looms, and more especially to automatic looms of that type wherein the filling is removed by replacing the exhausted shuttle with another shuttle.

In order that the principle of the invention may be readily understood, I have disclosed a single embodiment thereof in the accompanying drawings, wherein—

Figure 1 is a front elevation of the right hand end of a loom constructed in accordance with my invention;

Fig. 2 is an end elevation thereof;

Fig. 3 is an enlarged end elevation of the take-up mechanism;

Fig. 4 is a plan view of the right hand end of the loom;

Fig. 5 is a front elevation of the construction shown in Fig. 4;

Fig. 6 is a detail showing a portion of the feeler mechanism;

Fig. 7 is a vertical section of the construction shown in Fig. 6;

Fig. 8 is an end elevation of the mechanism shown in Fig. 4;

Fig. 9 is a front elevation, partially in vertical section, of the lay and parts adjacent thereto;

Figs. 10 and 11 are vertical sections respectively on the lines 10—10 and 11—11 of Fig. 9;

Fig. 12 is an end elevation partially in vertical section of the lower portion of the loom;

Fig. 13 is a plan view of the construction shown in Fig. 12;

Fig. 14 is a front elevation, partially in vertical section, of the construction shown in Fig. 12;

Fig. 15 is a view similar to Fig. 14, but of a portion only of the mechanism shown therein and illustrating the parts differently positioned;

Fig. 16 is a view similar to Fig. 12, but

upon a larger scale and showing only a part of the mechanism shown in the latter figure;

Fig. 17 is a detail in plan and longitudinal section of a portion of the feeler mechanism adapted to a bobbinless or coreless filling package in the shuttle;

Fig. 18 is a diagram illustrating the throw of the shuttle under different conditions;

Fig. 19 is an end elevation of the lower part of the loom, but showing a modified construction.

The loom of my invention may be used in various relations and for weaving various kinds of material. It is, however, so far as the disclosed embodiment is concerned, particularly adapted for weaving jute and other coarse and heavy fibers in the manufacture of gunny bagging.

In carrying out my invention the filling may be replenished in any suitable manner, but preferably by replacing the exhausted shuttle with a refilled shuttle. The filling supply may be in any suitable form or package, but in that type of loom to which I have particularly applied my invention, the filling supply is in the form of a bobbinless cop or package of yarn coiled into a generally cylindrical mass having preferably more or less tapering ends, and forced into the shuttle which may be of large size.

In an ordinary loom there is a brief time in the lay stroke when both boxes may be emptied of the shuttle and still not interfere with the picking or dagger actions of the loom, and the loom will run on uninterruptedly if the shuttle be restored to its original place at or before the expiration of such time. The limits of the period referred to are the passing of the frogs by the daggers on the forward stroke of the lay and the beginning of the picking action on the following back stroke of the lay.

If the filling motion be suspended for one pick or if there be no filling motion on the loom, the empty shuttle may be removed from its box during the period referred to and a refilled shuttle may be inserted in the opposite box. Such refilled shuttle may be put into the opposite box by sending it into the shed or without passing it through the shed provided the action of the filling motion be suspended temporarily and the take-up mechanism be similarly suspended.

The disclosed embodiment of my invention is based upon this general principle of

operation, and the removal of the empty shuttle and the entry of the refilled shuttle take place during the period referred to. Although I have shown my invention as applied to a shuttle having a bobbinless cog or package, it is understood that it is in no wise limited thereto.

Referring more particularly to the drawings, the sides of the loom are represented at 1, the breast beam at 2, the front girt at 3, the crank shaft at 4, the crank thereof at 5, the cam shaft at 6, the gear thereon at 7, the pulley or driving shaft at 8, the pinion meshing with the cam shaft gear 7 at 9, the rocker shaft at 10, the lay sword at 11, the lay at 12, and the connecting rods between the lay and the crank shaft at 13. These parts may be of any suitable or usual construction. The shuttle boxes themselves may be of any suitable character, and in Fig. 4, I have represented the back wall of the shuttle box at 14 and the front wall thereof at 15. One of the shuttles is represented at 16, such shuttle being the exhausted shuttle that has just been moved from its shuttle box and the refilled or new shuttle is indicated in dotted lines at 17 in Fig. 4. In accordance with the principle and preferred embodiment of my invention, I discharge the empty shuttle at one side of the loom and preferably introduce the new and refilled shuttle at the same side, and in Fig. 4 have represented the exhausted shuttle as discharged from and the refilled or new shuttle as introduced at the right hand side of the loom.

In carrying out my invention, I preferably provide a so-called transfer rod 18 horizontally mounted in suitable bearings generally indicated at 19 in the framing of the loom and adapted to receive both an axial movement and a rotative movement at the time when the transfer or change of shuttles is to be effected.

As shown most clearly in Figs. 14 and 15, the transfer rod 18 is provided with a bracket 20 having rolls 21, 21 mounted thereon and suitably spaced for the reception of a lever arm 22 mounted upon a shaft 23 and adapted periodically to be made fast with respect thereto, so that in the rocking movement of the said shaft, axial movement may be imparted to the transfer rod 18. The shaft 23 is constantly rocked but the lever arm 22 is only periodically made fast with said rock shaft and hence only periodically,—and that in the event of breakage or substantial or complete exhaustion of the filling—is axial or rotative movement imparted to the transfer rod 18.

Fast upon said rock shaft 23 is an arm 24 provided with a roll 25 adapted to enter a groove in the cam 26 upon the cam shaft 6, whereby a constant rocking movement is imparted to said shaft 23.

Fast upon the shaft 23 and as most clearly

represented in Fig. 14, is a bracket 27 here represented as made in a plurality of parts suitably secured to the said shaft and having pivotally mounted thereon at 28 a latch 29 provided in the upper face thereof with a notch 30 as shown most clearly in dotted lines in Fig. 14, said notch being adapted to be interengaged with a tooth 31 upon the portion 32 of the lever arm 22 which as previously described is normally loose upon the rocker shaft 23. Since the bracket 27 is fast upon said shaft, the interengagement of the tooth 31 and notch 30 will temporarily render the lever arm 22 fast upon the shaft 23, and hence said lever arm will partake of the rocking movement of said shaft and thereby at such times impart axial or longitudinal movement to the transfer rod 18.

In accordance with my invention, I provide means under the control of the feeler mechanism, and also, if desired and as herein shown, under the control of the filling fork, whereby the parts are temporarily connected and axial movement is imparted to said transfer rod 18.

While this result may be effected in any suitable manner, I have in the present embodiment of the invention shown the described movements of the transfer rod 18 as controlled by a feeler 33, which is adapted to enter an opening 34 in the front wall of the shuttle box and to feel through an opening 35 in the shuttle for the filling 36 therein. In the disclosed embodiment of my invention, such filling is wound in a coil or general cylindrical package, but without a core, and is forced or packed into the cavity 37 of the shuttle, such cavity generally having concaved or tapered ends, as indicated at 38 in Fig. 17. The yarn is built up in nested conical layers into a coreless package, the tips of the said layers pointing to the right in Fig. 17, and the yarn feeds off first from the left hand end of the shuttle, viewing said figure, and the feeler makes its indicating movement past the base of a conical layer near the tip of the package. Such yarn package may be held in place in the shuttle merely by friction or if desired by a strip 38' secured to the shuttle or in any other suitable manner. The filling is gradually withdrawn from the shuttle beginning from the left hand end thereof, viewing Fig. 17, and the feeler 33 in feeling for the filling is prevented from entering the shuttle until the filling has been exhausted to a predetermined extent and substantially to the extent indicated in said figure. When the filling has been exhausted to the extent there indicated, the feeler is permitted to enter past the edge or shoulder 39' of the remaining filling and therefore is permitted to make a relatively prolonged movement into the shuttle past said edge or shoulder 39'. This permits a more certain movement

of the parts controlled by said feeler. So far as I am aware, I am the first to employ a coreless package in the shuttle and to employ a feeler to enter the shuttle and feel for such package and to act upon such indication. As previously stated, however, my invention in all aspects thereof is not limited to the employment of such a type of feeler, nor to a shuttle having a coreless package, 5 although I obtain marked advantages in the use thereof. The feeler may be of any suitable type, and my invention is not limited to that form or character of feeler herein shown. In accordance with my invention, 10 the feeler feels for the receding or basal edge of the filling package preferably at or substantially at the inner surface of the wall of the shuttle, and when the edge or basal portion is found or felt, then the feeler moves 15 inwardly in effecting replenishment or functioning. Such inward movement is preferably a relatively great one, but my invention is not limited to such relatively great movement, inasmuch as so far as I am aware, I 20 am the first to effect replenishment of a shuttle carrying a coreless package where the feeler feels for the basal or edge portion of the package. My invention is not limited 25 to a construction wherein the feeler moves or functions when the precise or actual edge 30 or base of a layer is reached or felt, because the feeler may function just before the precise edge is reached as by crowding inward the last yarn or so of the basal portion, but 35 practically and in actual practice the feeler functions by feeling for the edge portion.

Moreover, the package is snugly positioned in the cavity of the shuttle, and the last portion of the package is tightly held 40 in position, as shown in Fig. 17, and is not displaced by the feeling action of the feeler. Moreover the feeler feels for the filling at the outer surface of the package; that is, at substantially the inner surface of the shuttle.

45 The feeler 33 extends through a lug or boss 40 upon a sleeve 41 loosely mounted upon a pin or stud 42 and secured in such position by a set screw 43. The said pin or stud 42 is mounted in any convenient position upon the lay of the loom and preferably as indicated in Fig. 9. Between the pin or 50 stud 42 and the outer sleeve 41 is an inner sleeve 44 also loose upon said pin or stud and having extending therefrom a lug 45 having therein an opening 46 into which takes the hooked end 47 of a link or wire 48, the opposite or inner end of which is pivotally connected at 49 to the upper arm 50 of a lever 51 pivoted at 52 upon a stud extending from the loom frame. The lower 55 arm 53 of said lever 51 is pivotally connected to a so-called equalizer rod 54, which is connected substantially midlength thereof to a link 55, itself pivotally connected at 56 60 to a bell crank lever 57 pivoted at 58 upon

a stud projecting from a bracket 59 upon the loom frame. The arm 60 of said bell crank lever 57 is suitably connected to the upper end of a so-called feeler rod 61 here shown as having nuts 62 between which is received the end of said arm 60. The said feeler rod 61 extends downwardly as indicated in Figs. 14, 16, etc., and is guided in an arm or bracket 63 fast upon the rocker shaft 10 of the lay sword. If desired, the 70 lower end of said feeler rod 61 may pass through an opening in a lug or projection 64 laterally extending from said arm or bracket 63 and into proximity to the upper end of an adjustable stop 65 upon a bracket 66 suitably supported upon the floor or other base.

Viewing Figs. 9, 16, 17, etc., it will be evident that as the lay moves backward, rocking about the shaft 10 thereof, the feeler rod 61 moving with the lay will engage the top 75 of the adjustable stop 65 and during the further movement of the lay will be lifted by reason of such engagement with the adjustable stop 65 and hence will through the described connections shown in Fig. 9, move 80 the feeler 33 out of or away from the shuttle. The movement of the feeler rod 61 without entry of the feeler into the shuttle is permitted because of the inner and outer sockets 41, 44 by which the feeler is supported. Said sockets have ears 67, 68 indicated most 85 clearly in Fig. 6 and connected by a coil spring 69.

As shown most clearly in Fig. 16, the feeler rod 61 passes through an opening 90 in a pawl 71 mounted upon a stud 72 upon the loom frame. Between said pawl and the upper end of the bracket 63 is a coil spring 64' tending constantly to depress said feeler rod 61 and below said pawl 71 is a 95 collar 73 to hold the pawl into proper position. The downward movement of the feeler rod 61 permits the tooth 74 of said pawl to engage one of the teeth 75 upon a ratchet 100 76 frictionally held upon a stud or short shaft 77 as most clearly indicated in Fig. 12. In order to hold said ratchet frictionally and to prevent over movement thereof, I have herein represented a friction clamp 105 78' as embracing and frictionally holding the stud or short shaft 77. As most clearly indicated in Fig. 14, the shaft 77 is provided not only with the ratchet 76 but with an adjacent ratchet 78, a cam 79 indicated in full lines in Fig. 16, and also a cam 80.

When the lay moves forward and the filling is in the shuttle, the feeler strikes the filling and this contact lifts the finger 71 before its point 74 passes the ratchet tooth 75, and thus avoids a transfer. This is the 110 normal action of the feeler. If however there be no filling in the shuttle, the feeler enters the shuttle and consequently affects the lowering of the rod 61 a little, thereby 115 delaying the lifting of the finger 71 suffi- 120 125 130

ciently to allow its point 74 to engage the said ratchet tooth 75 and thus cause a transfer. The finger 71 lifts some time on the forward stroke of the lay. If it is lifted by 5 the filling it is lifted before it reaches the tooth 75, but if it is lifted after the feeler has entered the shuttle it strikes the tooth 75 and turns the ratchet, thus initiating the ratchet action.

10 It will be understood from the foregoing that the feeler is forced positively out of the shuttle when the lay rocks backward and the rod 61 strikes the contact 65. Then when the lay rocks forward the rod 61 15 drops of its own weight or it may be assisted by the spring 64'. As it does so it brings the feeler into the shuttle at the proper time, controlled by the adjustment of the stop 65. Then if the feeler strikes the filling the 20 result is that hereinbefore described. It may be stated that the spring 69 yields when the feeler is positively forced out of the shuttle against the feeler action hereinbefore described, by the contact of the arm 154 with the latch 154'. That is to say, after 25 the feeler has done its work it must be pushed out of the shuttle to allow the latter to pass out of the box in transferring.

The engagement of the pawl 71 with a 30 tooth of the ratchet 76 effects a partial turning of the latter and permits the end of an operating pawl 81 to engage a tooth of the adjacent ratchet and also permits the tooth or extremity of the holding pawl 82 to engage 35 with a tooth of the ratchet 76 and prevent back movement thereof. The rotation of the ratchet 76 and consequently of the short shaft 77 effects a movement of partial rotation of the cam 80, and brings the same 40 beneath and into engagement with a downward projection 83 upon a pawl 84 shown most clearly in Fig. 16 and which as indicated in Figs. 12 and 14 extends beneath the lower end of a pin 85. The pin 85 is guided 45 in the bracket 27 and at its upper end takes under the pivoted latch 29 and lifts the same into engagement with the tooth 31, thereby through the previously described connections rendering the lever arm 22 periodically 50 fast with the constantly rocking shaft 23, and thus imparts longitudinal movement of the transfer rod.

Referring first to the feeler rod 61 and to the timing of the movements thereof and of 55 the related parts, I point out that in the preferable operation of parts and as disclosed herein, when the lay is back (that is, away from the weaver) the bottom end of the feeler rod 61 comes in contact with the 60 adjustable stop 65 a little before the shuttle has left the shuttle box and forces the feeler out of the shuttle, so that when the lay is clear back, the feeler is clear out of the shuttle. Conversely when the lay starts forward 65 (on the stroke which brings in the shuttle,

i. e. the one next following), the feeler starts inward and is timed by the adjustable stop 65 to reach the shuttle just after the arrival of the same. The feeler moving in all the time, however, touches the filling in the 70 shuttle after which its further inward movement is arrested by this contact. Consequently the finger 71, shown most clearly in Figs. 1, 2 and 16, cannot descend far enough to engage its point 74 with the ratchet tooth 75, and hence no transfer occurs. Should, however, the feeler go into the shuttle, a transfer would take place. When the feeler strikes the filling in the shuttle, this effects a lifting of the feeler rod 61 away from the 80 adjustable stop 65 at the time of no transfer. At the time of transfer, however, the feeler rod 61 is still lifted, though a little later, but this lifting is effected by the finger 71 in contact with the ratchet 75.

In this or in any other suitable manner, the feeler controls the movement of the transfer rod which as herein described effects the transfer of the new shuttle and the reception of the discarded shuttle.

I have stated that the movement of the feeler rod 61 may be effected either by the feeler or by the filling fork. In Figs. 9, 10 and 11, I have indicated one form of means whereby the filling fork will also be 90 caused to operate the feeler rod 61 in the event of breakage of the filling. For that purpose I have herein represented the filling fork at 86 as pivoted at 87 in the usual manner and having rigid therewith a laterally 10 extending lug 87' connected by a link 88 with the arm 89 of a bell crank lever 90, the lower arm 91 whereof is connected as indicated in Fig. 10 to the rod 54. The said rod 54, as previously stated, is connected 11 by the equalizer link 55 to the feeler rod 61. Thus through the described connection, either the filling fork or the feeler may be employed to initiate the shuttle transfer.

It is usually important that during shuttle 1 transfer, the take-up should be suspended. For that purpose I have provided the cam 79 heretofore described and which, as indicated most clearly in Fig. 16, engages and rocks a lever 92 pivoted at 93 and at its 1 lower end connected by a link 94 to a lever 95 pivoted at 96 and having at its upper end a shield 97 adapted to be interposed beneath the take-up pawl 98 shown most clearly in Fig. 3.

Any suitable take-up mechanism may of course be employed. Herein for the purpose I have provided a take-up roll 99 driven from a roll 100, the gear wheel 101 of which is driven by a pinion 102 upon the 1 short shaft 96. Fast upon said shaft 96 is a ratchet 103 with which engages the pawl 98, thereby to drive the same and to rotate the take-up. The take-up pawl 98 is mounted upon an arm 104, to which is 1

pivotedly connected a link 105 operated from the loom in any usual manner, not herein necessary to explain. By interposing in the described manner the shield 97 beneath the 5 pawl 98, the take-up is temporarily suspended. The ratchet 103 is held from backward movement by the pawl 106.

In the manner described, or in any other suitable manner longitudinal movement is 10 imparted to the transfer rod 18. In order to impart a movement of rotation thereto, I may employ any suitable means but preferably I mount on said rod as most clearly indicated in Fig. 8, an arm 107 having 15 thereon a roll 108 adapted to take against a spiral or other suitably shaped cam 109 upon the under side of the breast beam. The shape of said cam is such that the axial movement of said transfer rod causes a corresponding 20 movement of the roll 108 along the cam 109, and the latter imparts a suitable movement of partial rotation to the said transfer rod. The return movement of the transfer rod 18 is effected through the coiled 25 spring 110 interposed between the frame of the lay and the bracket 111 fast upon the said transfer rod.

Fast upon and upwardly extending from the transfer rod 18 are the arms 111, 112 30 each having a hub 113 secured to the transfer rod by set screw 114. The upper ends of said arms 111, 112 are provided with longitudinally extending sleeves 115 wherein is mounted for axial or sliding movement a 35 guide rod 116 which as most clearly shown in Fig. 4 is provided with a keyway 117 to prevent rotative movement thereof. On the outer end of said rod 116 is a picker member 118 by which the new or replenishing shuttle 17 is thrown into or over the shed and thence into the opposite box of the loom. Return movement is imparted to the rod 116 by a coiled spring 119 shown most clearly in Fig. 4.

45 Secured to the arms 111 and 112 and inwardly extending therefrom are arms or lugs which carry a receptacle, box or shelf adapted not only to support the new or replenishing shuttle but also the exhausted shuttle. While any suitable means may be provided for the purpose I have herein represented as secured to said lugs an auxiliary or transfer box 121 having a front wall 122 and a rear wall 123 between which said 50 new shuttle is received. I have herein indicated the said box 121 as occupying an inclined relation in a substantially horizontal plane, thereby permitting the replenishing shuttle to be thrown into or above the shed 55 at such an inclination that it finds its way into the opposite box and without interfering with the outgoing or discharged shuttle 16. The said transfer box 121 is provided with a laterally extending fin or shelf 60 65 124, of such form that when the transfer

box 121 is moved into the position shown in Fig. 4, said fin or shelf 124 will receive thereon the discharged shuttle 16. The said fin or shelf 124 is provided at its inner end with a box-like member 125 having therein 70 an impact member 126 for the shuttle 16. The said discarded shuttle 16 may readily be removed by hand from the said fin or shelf, but I prefer to have the recoil of spring 110 throw it out. 75

The construction and relation of parts are such that the filling feeler will be out of the shuttle at the time of shuttle flight or when the lay is back of the center and will be in feeling position during the rest of the time. 80 The amount of filling to be held in reserve in order to complete the pick will depend upon the nature of the fabric being woven. Inasmuch as the mechanism herein shown operates quickly enough to function upon the 85 immediate lay stroke, I prefer when weaving gunny fabrics to place the feeler on the same side of the loom from which the empty shuttle is expelled, and then allow the shuttle to be completely exhausted before transfer, 90 or I may reserve one full pick according to the nature of the fabric.

I provide means to prevent the feeler from acting or functioning when the shuttle is on the opposite side of the loom from that at 95 which the feeler is located or otherwise the feeler would act in the absence of a shuttle, and by moving downward the feeler rod 61 would cause the replenishing mechanism to function. Therefore I provide what I term 100 an alternating mechanism to prevent the functioning of the feeler when the shuttle is not in the box at that side of the loom. While for this purpose I may provide any suitable means, I have in Fig. 12 represented 105 the cam shaft 6 as having thereon a cam 127 adapted to act upon the end 128 of a lever arm 129 pivoted at 130 upon a standard or bracket 131. Rigid with the lever arm 129 is a downwardly extending arm indicated in dotted lines at 132 in Fig. 12, and having an enlargement 133 adapted to engage the lower end 134 of a lever arm 135 rigid with the operating pawl 81, shown most clearly in Fig. 16. The action of said 110 cam 127 therefore is to hold the feeler from functioning whenever the shuttle is not in the box at the right hand side of the loom, by preventing the operating pawl 74 (Fig. 16) from imparting rotative movement to 115 the cams 79 and 80. 120

In Fig. 19, I have shown a slightly modified form of my invention. Therein the feeler rod 61 is supported at its lower end by a bracket 136 through which it passes and 125 above which is positioned a coil spring 137 held compressed by a collar 138 and tending normally to elevate said feeler rod 61. Pivoted at 139 is a dog 140, the tooth of which is positioned between collars 141 upon the 130

feeler rod 61 so as to move up and down therewith and periodically brought into the range of a tooth 142 upon a pawl 143 pivoted at 144 to a link 145 itself pivoted at 5 146 upon a portion of the loom frame or stationary bracket, as shown. Whenever the feeler rod 61 is depressed by the indicating action of the feeler, the dog 140 engages the tooth of the pawl 143 and through the link 10 145 rocks the lever 147 mounted upon the pivotal pin 146, thereby elevating the pin 85 in the manner previously described.

In order to prevent the functioning of the shuttle replenishing mechanism when the 15 shuttle is not in the box at the right hand side of the loom, I provide substantially the mechanism shown in Fig. 12, and for that purpose I provide upon the cam shaft 6 a cam 148 to engage the end 149 of the lever 20 arm 150 pivoted upon the stud 151 upon the bracket 152 and having fast therewith an arm 153 adapted to take under and engage and periodically permit to fall the pawl 143, so that it will be out of the path of movement of the dog 140.

By the foregoing construction, a whole pick would be lost by a shuttle getting into the opposite box at the time of transfer without laying a strand in the fabric. I 30 may provide any suitable means to prevent the loss of a pick or to prevent the loss of a partial pick. Some fabrics are of such character as to admit of a part of the pick being absent. In such cases, I may provide 35 suitable means, as for example a guide or deflecting member with which the incoming shuttle engages, so that the incoming shuttle will strike the same and be deflected into the shed part way across the loom. With such mechanism I need not interrupt the working 40 of the take-up.

The feeler mechanism herein described and broadly feeler means to act or feel against the receding edge or retreating edge 45 of a bobbinless cop or package may be employed in connection with other types of replenishing mechanism and for example the same may be used in connection with replenishing packages for shuttles, in which case 50 if desired a battery of packages or even a battery of shuttles may be employed.

Preferably the timing of the ingoing or replenishing shuttle is later than the outgoing action of the exhausted shuttle, thus 55 allowing the outcoming shuttle to emerge from its box over a flat shed, while the ingoing shuttle arrives when the shed is opened, thus making it possible to enter the shed itself and avoid stopping the take-up.

In order to operate the picker stick so as 60 at the proper time to discharge the exhausted shuttle, I may provide any suitable means, but I have in Fig. 4 represented a connecting rod 154 serving as a supplemental picker stick and for that purpose

pivotedly connected at one end 155 to the outer end of the transfer rod 18 so as to be moved thereby in the axial movement of the latter but without partaking of the rotative movement thereof. The opposite end of the 70 connecting rod 154 is pivotally connected at 156 to a link 157, itself pivotally connected at 158 upon a bracket 159 extending from the frame of the loom. The connecting rod 154 is so positioned as to engage the picker 75 stick at the proper time and thereby impart a supplemental movement thereto and eject the exhausted shuttle.

The connecting rod 154 lifts the lever 154' represented in dotted lines at the extreme 80 right in Fig. 5 and in full lines in Fig. 9, and throws the feeler out of the slot in the shuttle just before the exhausted shuttle is thrown onto the shelf 124. Otherwise the feeler 33 might hook the shuttle and prevent 85 the proper ejection thereof.

The mechanism herein described may be adjusted or set to effect shuttle transfer from the feeler either when there is enough weft 90 left in the shuttle to cross the fabric at least once, in which case the take up must on plain weave be stopped twice and the transfer must take place on the third lay stroke, the mechanism as illustrated being set to effect this result. The mechanism, however, may 95 be set to act when there is no weft in the shuttle, or not enough for a single pick. In the former case, no empty or partially empty pick occurs, but a double thread pick is permitted, and in the latter case a partial pick 100 is permitted. The parts may be changed from the one setting to the other by adjustment of the ratchets and co-acting parts shown in Figs. 14 and 16. The shuttle may therefore be sent in to the opening shed to 105 supply the necessary partial pick.

In the former setting the shuttle is not sent in to the shed and therefore on the second pick after the indicating feeling action, the take-up must be stopped, and as the 110 shuttle is likely to exhaust on the return pick, which return pick must again be laid with a complete thread, the take-up must be stopped for this pick also, thus making two stops for the take-up.

The diagram in Fig. 18 is intended to indicate the points at which the take-up must stop. The interrupted lines at the angles 3, 4 on said diagram indicate an interrupted take-up. The light line 2, 3 indicates the path of an empty shuttle, the dotted lines 3, 4 indicate no shuttle, the light curve near the angle 3 indicates the time or point at which the empty shuttle leaves the box, and the full curve near the angle 4 indicates where the replenished shuttle enters. The letter F indicates where the feeding action occurs, and the letter T where the transfer occurs.

By varying the mechanism with respect to 130

the number of teeth and size and shape thereof and the position of the cams, I am enabled to match the pick on any ordinary shade, since the empty shuttle can be sent 5 back and forth and the cam mechanism may be sent for transfer where the original shed opens. In the case of odd shades, I may supply enough teeth to double the cycle, thus bringing the shuttle back to the battery end 10 of an even number, stopping the take-up in the meanwhile and starting in the new shuttle on the original pick.

Certain features of my invention are adapted to a loom wherein the filling is carried 15 upon a bobbin in the shuttle or other suitable core or support. That is, although I have disclosed and preferably employ a coreless package composed of nested cones, past the base of one of which the feeler 20 finally moves in its indicating movement, my invention is not restricted thereto so far as many features of the invention are concerned.

With respect to the transfer rod 18 and 25 the box 121, it is pointed out that the recovery of said rod and box will in practice develop a motion sufficient to eject the exhausted shuttle into a receptacle, and therefore will reduce the tension required by the 30 weaver.

The rod 116 does not in the ordinary sense serve to pick the shuttle out, but together with the spring 119 serves as a yielding motion to delay the time of the shuttle's departure 35 from its transfer box, so that the lay will have more time to open its shed in order that the shuttle may enter therein. That is to say, the new shuttle would be picked out from its transfer box if the rod 40 116 and the spring 119 were omitted, but it would leave the same at the same time that the outcoming shuttle leaves the shuttle box of the loom which is intentionally on the flat shed. The spring 119, therefore, serves 45 to delay slightly the introduction of the new shuttle.

Within the broad scope and purpose of my invention, I may instead of employing a spare shuttle, employ a battery to support 50 filling carriers of any suitable type and construction, or I may employ a battery to support a plurality of shuttles. It will be understood from the foregoing description that if there be no shuttle in the transfer box or 55 in the battery to replace the outcoming or discharged shuttle, the loom will at once stop on the dagger action. The loom will automatically stop either from the exhausted shuttle or from a broken weft 60 thread because either of them will call for a transfer. If I employ a battery to support shuttles or weft carriers, I will employ a suitable thread holder, the thread extending from each shuttle or filling carrier to some 65 part of the battery or loom, so as to start

the shuttle filling action. Such thread holder is preferably in the form of a clamp located either at the top end of the arm 112 as shown in Fig. 5, or it may be located near the opposite selvage of the cloth in case 70 the new shuttle does not enter the shed half way across. In such latter case, yarn would be saved. The purpose of employing a clamp is to allow the thread to draw out therefrom as the cloth feeds along. 75

So far as I am aware, I am the first to provide a jute or similar heavy weft loom having a coreless package in the running shuttle, with means to effect replenishment of the filling, and desire to claim the same 80 broadly. While in the disclosed embodiment of my invention, I have illustrated replenishment by supplying a new shuttle, I may effect replenishment by inserting a new filling package into the running shuttle. I 85 may, however, feel for the filling on a regular bobbin.

While I have herein disclosed means for supplying a new shuttle and means for discharging the exhausted shuttle, it is to be 90 understood that in certain aspects of my invention, either of said means may be used irrespective of the other. Thus, if I provide means for discharging the exhausted shuttle, means other than that shown may 95 be provided to supply a new shuttle, and furthermore, the means for discharging the exhausted shuttle may be employed whether or not means be provided to supply a new shuttle. 100

Having thus described one illustrative embodiment of my invention, I desire it to be understood that although specific terms are employed, they are used in a generic and descriptive sense and not for purposes of 105 limitation, the scope of the invention being set forth in the following claims.

Claims:

1. A weft replenishing loom having a support for a spare shuttle at one side of the 110 loom, means to pick that spare shuttle from its support across the loom, thereby bringing it into play, and means to discharge the exhausted shuttle in a direction longitudinally of the lay and of the shuttle from the 115 shuttle box at that side of the loom where the spare shuttle is supported and to receive the said discharge exhausted shuttle at said side of the loom where the spare shuttle is supported, whereby the exhausted shuttle 120 in the discharge movement thereof is received at the same side of the loom as that from which it is discharged.

2. A weft replenishing loom having means to insert the new shuttle at an angle to the 125 top of the lay and to discharge a shuttle axially of the lay.

3. A weft replenishing loom having at one side thereof a transfer box, means to move said box into a substantially hori- 130

- zontal position at an angle to the top of the lay, means to discharge the shuttle from said box and means to discharge a shuttle from the loom axially of the lay.
5. A weft replenishing loom having at one side thereof a transfer box, means to rock said box into a position inclined to the top of the lay and means automatically to drive the new shuttle from said box into the opposite shuttle box of the loom.
10. A weft replenishing loom having at one side thereof a transfer box, means to rock said box so as to bring the same into a substantially horizontal position but inclined to the top of the lay, means automatically to eject the new shuttle from said transfer box and means carried by said transfer box to receive the exhausted shuttle.
15. A weft replenishing loom having at one side thereof a transfer box, means to rock said box toward the lay, means automatically to discharge the new shuttle from said box into the opposite shuttle box of the loom and a spent shuttle support carried by said transfer box and adapted to be positioned by the rocking of said box toward the lay to receive the spent shuttle.
20. A weft replenishing loom having a transfer rod, means to impart axial and rotative movement to said rod and a new shuttle transfer box supported and moved by said transfer rod.
25. A weft replenishing loom having a transfer rod, means to impart axial and rocking movement to the latter, a new shuttle transfer box supported and moved by said transfer rod and means carried by said transfer box to receive the exhausted shuttle.
30. A weft replenishing loom having a horizontally positioned transfer rod, means to impart axial and rocking movement thereto, a transfer box supported thereby to hold the new shuttle and to receive the exhausted shuttle and means controlled by the filling to govern the movements of said transfer rod.
35. A weft replenishing loom having a transfer box at one side of the loom to hold the new shuttle and to receive the exhausted shuttle and means governed by the filling to rock said transfer box into position to permit the insertion of the new shuttle and the reception of the exhausted shuttle without interference with each other.
40. A weft replenishing loom having a rock shaft, a transfer rod, means periodically to impart axial movement from said rock shaft to said transfer rod and means supported by said transfer rod to carry the new shuttle and to receive the exhausted shuttle.
45. A weft replenishing loom having a rock shaft to said transfer rod, means supported by said transfer rod to carry the new shuttle and to receive the exhausted shuttle and means controlled by the filling to determine the periods of movement of said transfer rod.
50. A weft replenishing loom having a horizontally positioned transfer rod, means to impart axial and rotative movement thereto, a transfer box supported by said rod to contain the new shuttle and to receive the exhausted shuttle, picker mechanism and supplemental means to discharge the exhausted shuttle on to said transfer box.
55. A weft replenishing loom having at one side thereof a transfer box to hold the new shuttle and to receive the exhausted shuttle, normally acting picker mechanism and supplemental picker means to discharge the exhausted shuttle from its box on to said transfer box.
60. A weft replenishing loom having at one side thereof a transfer box to hold the new shuttle and to receive the exhausted shuttle, normally acting picker mechanism, supplemental picker means to discharge the exhausted shuttle from its box on to said transfer box and means to drive the new shuttle from said transfer box into the opposite shuttle box of the loom.
65. A weft replenishing loom having at one side thereof a transfer box to hold the new shuttle and to receive the exhausted shuttle, means to feel for the filling in the running shuttle, means controlled by said feeler means to discharge the new shuttle from said transfer box into the opposite shuttle box and means also controlled by said feeler means to discharge the exhausted shuttle on to said transfer box.
70. A weft replenishing loom having at one side thereof a transfer box having a laterally extending shelf to receive the exhausted shuttle, supplemental picker means to act upon the exhausted shuttle and to drive the same on to said shelf, means to discharge the new shuttle into the opposite box of the loom and means controlled by the filling to govern the action of said supplemental picker means and the means to discharge the new shuttle from said transfer box.
75. A weft replenishing loom having at one side thereof a transfer box provided with means to receive the exhausted shuttle, and means controlled by the filling to discharge the new shuttle from said transfer box into the shuttle box at the opposite side of the loom and to discharge the exhausted shuttle into the said receiving means therefor.
80. A weft replenishing loom having at one side of the lay a transfer box to contain a new shuttle and to receive the exhausted shuttle.

shuttle, supplemental picker means to discharge the exhausted shuttle into said receiving means therefor, and means controlled by the condition of the filling to govern the action of said supplemental picker means.

20. A weft replenishing loom having a shuttle to receive a coreless package of filling, means exterior to said package to hold the diminishing filling package in position in the shuttle until substantial exhaustion, and means mounted exteriorly of the shuttle to feel for and to contact with said filling in the shuttle.

21. A weft replenishing loom having a shuttle adapted to contain a coreless package of filling and means periodically to enter past the outer surface of said shuttle and to feel for and to contact with said coreless package of filling therein and means rendered operative by engagement of said feeling means with the normally positioned tip end of said coreless package.

22. A weft replenishing loom having a shuttle to receive a coreless package of filling and a feeler mounted exteriorly of the shuttle and adapted periodically to contact with said filling and to move past the edge or shoulder of the said filling package when the same has been exhausted to a predetermined extent.

23. A weft replenishing loom having a shuttle to receive a coreless package of filling, means governed thereby to supply new filling to the loom when said coreless package of filling has become substantially exhausted, said shuttle having provisions whereby the filling package is engaged externally and thereby the diminishing portion is held in position until the governing means to supply new filling functions, and coöperating actuating means positioned to enter substantially past the shuttle wall only when the filling has become substantially exhausted.

24. A weft replenishing loom having a shuttle to receive a coreless package of filling, means governed thereby to supply new filling to the loom when said coreless package of filling is exhausted to a predetermined extent, said shuttle having provisions whereby the filling package is engaged externally and thereby the diminishing portion is held in position until the governing means to supply new filling functions, and coöperating actuating means positioned to enter substantially past the shuttle wall only when the filling has become substantially exhausted.

25. A weft replenishing loom having a shuttle adapted to contain a coreless package of filling, a feeler adapted intermittently to contact with said filling and means whereby said feeler makes a relatively

great inward movement past the edge or shoulder of the remaining filling in said shuttle.

26. A weft replenishing loom having a shuttle adapted to contain a coreless package of filling, a feeler adapted intermittently to contact with said filling, means whereby said feeler makes a relatively great inward movement past the edge or shoulder of the remaining filling in said shuttle and means governed by said relatively great feeler movement to introduce new filling into the loom.

27. A weft replenishing loom having a shuttle adapted to contain a coreless package of filling, a feeler adapted intermittently to contact with said filling, means whereby said feeler makes a relatively great inward movement past the edge or shoulder of the remaining filling in said shuttle and means governed by said relatively great feeler movement to introduce the replenishing shuttle into the loom.

28. A weft replenishing loom having a shuttle adapted to contain a coreless package of filling, a feeler adapted intermittently to contact with said filling, means whereby said feeler makes a relatively great inward movement past the edge or shoulder of the remaining filling in said shuttle and means governed by said relatively great feeler movement to drive a new shuttle into the shuttle box of the loom opposite the shuttle box where said feeler is located.

29. A weft replenishing loom having a shuttle adapted to contain a coreless package of filling, a feeler adapted intermittently to contact with said filling, means whereby said feeler makes a relatively great inward movement past the edge or shoulder of the remaining filling in said shuttle and means governed by said relatively great feeler movement to drive a new shuttle into the shuttle box of the loom opposite the shuttle box where said feeler is located and to discharge said shuttle into which the feeler entered.

30. A weft replenishing loom having at one side thereof and distinct from the usual shuttle box at said side of the loom, a movable transfer box to hold the new shuttle and to receive the exhausted shuttle, a filling fork, a feeler for the filling in the running shuttle, and means controlled by said filling fork and by said feeler to move said transfer box for replenishing.

31. A weft replenishing loom having at one side thereof and distinct from the usual shuttle box at said side of the loom, a transfer box to hold the new shuttle and to receive the exhausted shuttle, a filling fork, a feeler to feel for the filling in the running shuttle, and means controlled both

by said filling fork and by said feeler to effect the discharge of the running shuttle into said transfer box and the introduction of the new shuttle from said transfer 5 box.

32. A weft replenishing loom having at one side thereof a transfer box to hold the new shuttle and to receive the exhausted shuttle, a filling fork, a feeler to feel for the filling in the running shuttle and means controlled both by said filling fork and by said feeler to rock said transfer box into 10 position to permit the discharge of the new shuttle therefrom into the opposite box of the loom and to receive the exhausted shuttle 15 at the side of the loom having said feeler.

33. A weft replenishing loom having at one side thereof a transfer box to hold the new shuttle and to receive the exhausted shuttle, means to feel for the filling in the running shuttle, means controlled by said feeler means to discharge the new shuttle from said transfer box into the opposite 25 shuttle box, means also controlled by said feeler means to discharge the exhausted shuttle on to said transfer box and means to suspend the take up during replenishing.

34. A weft replenishing loom having a 30 rock shaft, a transfer rod, a lever arm, means periodically to connect said lever arm to said rock shaft and thereby to operate said transfer rod through said lever arm and means to effect said periodic connection upon filling fault.

35. A weft replenishing loom having a 35 rock shaft 23, a lever arm 22, means periodically to connect said rock shaft and lever arm, a transfer rod 18, operatively connected to said lever arm, and a transfer box adapted to contain a new shuttle and to receive an exhausted shuttle, said transfer box being operatively connected to said transfer rod.

45. 36. A weft replenishing loom having a rock shaft 23, a lever arm 22, means controlled by filling fault periodically to connect said shaft and lever arm, an axially and rotatably movable transfer rod 18, operatively connected to said lever arm and a transfer box supported and moved by said transfer rod.

37. A weft replenishing loom having a 55 shuttle to receive a package of filling, a transfer box to contain a new shuttle and to receive the exhausted shuttle at the same side of the loom as that at which it receives its discharging movement, and operative connections between the package in the running shuttle and said transfer box constituting means whereby a new shuttle is automatically supplied in the direction of its longer axis at a time determined by the

condition of the package in the running shuttle.

38. A weft replenishing loom having a running shuttle adapted to contain a package of filling, a feeler to feel for said package and to undergo an indicating movement when said package has become nearly exhausted, a transfer box to receive the exhausted shuttle at the same side of the loom at which said exhausted shuttle receives its discharging movement, said transfer box being constructed to contain the new shuttle, 75 and operative connections between said feeler and said transfer box and including means whereby the new shuttle is automatically supplied in the direction of its longer axis in conformity with said indicating 80 movement.

39. A weft replenishing loom having new filling supplying means, a feeler and a filling fork operatively connected to said new filling supplying means, an equalizer between and operatively connected with said feeler and filling fork and permitting either the feeler or the filling fork to initiate the action of the filling supplying means, said equalizer being movable in a direction transverse to its longitudinal axis under the influence of either the feeler or the filling fork, and a connection from said equalizer to the filling supplying means.

40. A weft replenishing loom having new 95 filling supplying means, a feeler and a filling fork both operatively connected to said new filling supplying means, an equalizer rod 54 between and operatively connected with said feeler and filling fork and permitting either the feeler or the filling fork to initiate the action of the filling supplying means, said equalizer being movable in a direction transverse to its longitudinal axis under the influence of either the feeler or the filling fork, and a connection from said equalizer to the filling supplying means.

41. A weft replenishing loom having a feeler rod 61, a feeler adapted to feel in the shuttle for the filling therein and operatively connected to said feeler rod, means normally to lift said feeler rod during each backward movement of the lay and means downwardly to move said feeler rod when said feeler indicates replenishing.

42. A weft replenishing loom having a feeler rod 61, means to move said feeler rod downward upon substantial exhaustion of the filling and means whereby said downward movement of the feeler rod introduces 121 a new shuttle at one side of the loom but into the shuttle box at the opposite side thereof.

43. A weft replenishing loom having a 122 feeler rod 61, a feeler for the filling in the running shuttle and operatively connected

to said feeler rod and whereby axial movement is imparted to said feeler rod and cam and ratchet means initiated in action by said feeler rod to control weft replenishment and 5 cloth take up.

44. A weft replenishing loom having a feeler to feel for the filling in the shuttle, a feeler rod 61 distinct from but operatively connected to said feeler, means to move said 10 feeler rod axially upon substantial exhaustion of the filling and consequent inward movement of said feeler, ratchet, pawl and cam means initiated in action by said axial movement of the feeler rod, and weft replenishing means operated by said ratchet pawl and cam means.

45. A weft replenishing loom having a feeler adapted to feel for the filling in the running shuttle, a feeler rod 61 having a 20 movable connection with said feeler, a pawl 71 controlled by said rod 61, a ratchet 76 controlled by said pawl, a cam 80 controlled by said ratchet, and a pawl 84 controlled by said cam.

25 46. A weft replenishing loom having a feeler rod 61, a pawl 71 controlled thereby, a ratchet 76, cam 80 and pawl 84 controlled by the pawl 71, lever arm 22, rock shaft 23, and means controlled by pawl 84 periodically to connect said lever arm and rock shaft.

35 47. A weft replenishing loom having a shuttle transfer box and means to move said box forwardly and downwardly toward the lay and to position the same for shuttle replenishment at an incline in advance of the lay.

40 48. A weft replenishing loom having a shuttle transfer box normally positioned above and in advance of the lay, means to move said box forwardly and downwardly toward the lay and into replenishing position in advance of the lay and level but inclined at its inward end toward the opposite 45 shuttle box of the lay.

50 49. A weft replenishing loom having a transfer rod 61, a feeler adapted to feel for the filling in the filling carrier and controlling the replenishing movement thereof, and operatively connected with said transfer rod 61 a take-up and a cam 79 controlled by said feeler rod to suspend the take-up.

55 50. A weft replenishing loom having a transfer rod 18, weft replenishing means operatively connected thereto and a cam on the breast beam to impart rotative movement to said transfer rod 18.

51. A weft replenishing loom having a transfer rod 18, means to impart rotative 60 and axial movement thereto, a transfer box supported and moved by said transfer rod, a guide rod 116 having axial movement, and a picker member for the shuttle in said transfer box and connected to said guide 65 rod 116.

52. A weft replenishing loom having a transfer rod 18, means to impart axial and rotative movement thereto, a new shuttle transfer box supported by said transfer rod, a guide rod 116 and a picker carried by the 70 guide rod to pick the new shuttle from said transfer box into the shuttle box at the opposite side of the loom.

53. A weft replenishing loom having a new shuttle transfer box which in transfer 75 position is substantially level but is forwardly inclined in a substantially horizontal plane toward the opposite shuttle box of the loom.

54. A weft replenishing loom having a 80 rocking transfer box and means to position said box for transfer in front of the lay and substantially level but inclined in a substantially horizontal plane toward the opposite shuttle box of the loom.

85 55. A weft replenishing loom having a transfer box and means to rock the same from a position above and in front of the lay downward to replenishing position close to the lay and substantially level but forwardly inclined toward the same.

56. A weft replenishing loom having a transfer box at one side of the loom to contain the new shuttle and to receive the exhausted shuttle, a feeler controlling the 95 movement of said transfer box, and means to prevent the feeler from functioning when the running shuttle is on the opposite side of the loom from said transfer box.

57. A weft replenishing loom having re- 100plenishing mechanism, a feeler controlling the same, an alternating mechanism to prevent functioning of said feeler, said alternating mechanism including cam 127, lever arm 129 and pawl 81.

58. A weft replenishing loom having at 110 one side thereof means to support the new shuttle and to receive the exhausted shuttle at the same side of the loom as that at which the exhausted shuttle receives its discharging movement toward said means and means to discharge the new shuttle at a later time than the outgoing movement of the exhausted shuttle.

59. A weft replenishing loom having a 115 transfer rod 18, a transfer box for the new shuttle and supplemental picker means for the old shuttle operatively connected to said transfer rod.

60. A weft replenishing loom having at 120 one side thereof a transfer box for the new shuttle and provided with a shelf for the exhausted shuttle, supplemental picker means for the old shuttle operatively connected to said transfer rod, and means con- 125 trolled by filling fault to pick the new shuttle from said transfer box.

61. A coarse filling loom provided with a shuttle having a skewerless cavity receiving a coreless filling package, means exterior to 130

- 5 said package to hold the diminishing package in substantially its original position in the shuttle until replenishment and means exterior to the shuttle and governed by the condition of the filling package to effect replenishment, said means being substantially restrained by said package from entering past the shuttle wall until the condition of the filling is such as to cause replenishment.
- 10 62. A coarse filling loom having a running shuttle provided with a coreless coarse filling package, means exterior to said package to hold the diminishing package in substantially its original position in the shuttle until replenishment and means governed by said package to discharge the running shuttle and to introduce a new shuttle and including feeler means restrained from entering substantially past the wall of the running shuttle until the condition of the filling is such as to cause replenishment, whereupon said feeler means substantially enters the shuttle cavity.
- 15 63. A loom having means controlled by filling fault to eject the running shuttle at one side of the loom and to pick a new shuttle into the shuttle box at the opposite side of the loom, said means including feeler means restrained by the original surface of the filling package of the running shuttle from entering the running shuttle substantially past the inner surface of said shuttle, until the condition of the filling therein is such as to cause replenishment, and means external to the filling package to maintain the diminishing package with its original surface in substantially its original position until replenishment.
- 20 64. A coarse filling loom provided with a running shuttle carrying a coreless coarse filling package, means initiated in action by the substantial exhaustion of said package to discharge the running shuttle at one side of the loom and to introduce the new shuttle momentarily thereafter into the shuttle box at the other side of the loom, and movement-initiating means mounted wholly exteriorly of the shuttle and entering the same only when making a replenishment initiating movement.
- 25 65. A loom having a shuttle provided with a coreless package composed of nested conical layers and a feeler to feel for the filling of said package and to function by inward movement past the base of one of said nested cones, and weft replenishing means operated by the functioning of said feeler.
- 30 66. A loom having a shuttle provided with a coreless package composed of nested conical layers, shuttle replenishing mechanism, and a feeler operatively connected to said replenishing mechanism and adapted to cause the actuation thereof by inward movement past the base of one of said nested conical layers.
- 35 67. A weft replenishing loom having a rock shaft 23, a lever arm 22, means periodically to connect said rock shaft and lever arm, a longitudinally movable transfer rod 18 operatively connected to said lever arm, and means controlled by filling fault to effect the periodic connection of said rock shaft 23 and lever arm 22.
- 40 68. A weft replenishing loom having means to insert the new shuttle in a direction diagonally toward the reed of the lay.
- 45 69. A weft replenishing loom having means to insert the new shuttle at an angle to the top of the lay and about midway between the selvages of the fabric.
- 50 70. A weft replenishing loom having means to insert the new shuttle at an angle to the top of the lay when the reed is retreating and the shed opening, thereby permitting the nose of the shuttle to enter the shed.
- 55 71. A loom, a running shuttle whereof is provided with a skewerless cavity having a coreless filling package crowded into and wholly filling said cavity, means external to said package to hold the diminishing package in substantially its original position until replenishment, and feeler means wholly isolated from said shuttle and adapted periodically to co-act with said package and governed by the condition of the package in said cavity to effect weft replenishment.
- 60 72. A loom having a running shuttle provided with a coreless package crowded into the cavity thereof, means external to said package to hold the diminishing package in substantially its original position until replenishment, means governed by said package to discharge the running shuttle and to introduce a new shuttle, and a governing feeler adapted to contact with the outer surface only of the package until replenishing indication and restrained from entering substantially past the shuttle wall until the time arrives to effect replenishment.
- 65 73. A loom having a shuttle carrying a filling package, a feeler adapted to contact only with the original outer surface of said package in the shuttle until replenishment indicating movement of the feeler, means external to said package to hold the diminishing package in substantially its original position until replenishment, and means whereby upon such indicating movement replenishment is effected.
- 70 74. A loom having a running shuttle provided with a coreless package, means governed by the condition of said package to throw a new shuttle into the shuttle box at the side of the loom opposite that where the said governing means is located, and indicating means having a relatively long

shuttle entering indicating movement past a shoulder of said package when the time for replenishment occurs.

75. A loom having means controlled by filling fault to eject the running shuttle by ejecting movement thereof in a direction axially of the shuttle and wholly confined to one side of the loom, whereby the said shuttle in its ejecting movement does not cross the loom, and means to pick a new shuttle into the shuttle box at the opposite side of the loom in its entering movement.

76. A weft replenishing loom having a running shuttle adapted to contain a coreless package of filling means external to said package to hold the diminishing package in substantially its original position until replenishment, a feeler to feel for said coreless package and to undergo an indicating movement when said coreless package has become nearly exhausted, means to prevent displacement of the filling package in said cavity prior to replenishment, whereby the feeler is permitted to be governed accurately in its functioning by the extent of exhaustion of said package, a transfer box to contain the new shuttle, and operative connections between said feeler and said transfer box.

77. A weft replenishing loom having a transfer box at one side of the loom to hold the new shuttle, and picker means to drive said shuttle into the opposite regular box on the forward part of the lay stroke.

78. A weft replenishing loom having a transfer box at one side of the loom to hold a new shuttle, picker means to drive said shuttle into the opposite regular box, and auxiliary picker means to drive the exhausted shuttle from its regular box.

79. A weft replenishing loom having a transfer box at one side of the same to hold the new shuttle, means to feel for the filling, and means controlled by said feeler to drive said shuttle into the opposite regular box on the forward part of the lay stroke.

80. A weft replenishing loom having a transfer box at one side of the same to hold the new shuttle, feeler means, and a weft fork each adapted to be controlled by the filling, and means under the control of said feeler and said filling fork to drive said shuttle into the opposite regular box on the forward part of the lay stroke.

81. A weft replenishing loom having means to discharge the shuttle, and means to insert a new shuttle between the dagger action on the forward beat of the lay and the picking action on the next ensuing return stroke of the lay.

82. A weft replenishing loom having a cycle controlling shaft, pawls to control said shaft, means to feel for the weft, operative connections between said weft feeling means and said pawls and including an axially movable rod pivotally connected to said weft

feeling means, and replenishing means controlled by said shaft.

83. A weft replenishing loom having a cycle controlling shaft, pawls to operate the same, one of said pawls having an elongated tooth, and weft replenishing means controlled by said shaft.

84. A weft replenishing loom having a cycle controlling shaft, a ratchet to operate said shaft, said ratchet having an elongated tooth, an operating pawl for said ratchet, a starting pawl for said ratchet, and means controlled by the state of the filling, whereby the said starting pawl is thrown into the action.

85. A weft replenishing loom having at one side of the loom, a transfer box for the new shuttle and a receptacle for the exhausted shuttle, said receptacle and box both being supported by the frame of the loom, distinct from the lay, and means to move said receptacle and box in unison.

86. A weft replenishing loom having at one side of the loom a transfer box for the new shuttle and a receptacle for the exhausted shuttle, said receptacle for the exhausted shuttle being supported distinct from the lay and adapted to receive the exhausted shuttle directly from that side of the loom where the transfer box is located.

87. A weft replenishing loom having at one side of the loom a transfer box for the new shuttle and a receptacle for the exhausted shuttle, said receptacle and box being both movably mounted, and means to feel for the filling in the shuttle to move said receptacle and box for replenishment.

88. A weft replenishing loom having at one side of the loom a transfer box for the new shuttle and a receptacle for the exhausted shuttle, and means to discharge the exhausted shuttle into said receptacle horizontally from that end of the lay adjacent to which said receptacle is located.

89. A weft replenishing loom having at one side thereof a transfer box for the new shuttle, said box being provided with a laterally extending shelf to receive the exhausted shuttle, said transfer box and shelf being movably mounted independently of the lay.

90. A weft replenishing loom having at one side thereof, a transfer box to receive the exhausted shuttle, said box being movable from non-receiving to receiving position, a filling fork, a feeler for the filling in the running shuttle, and means controlled by said filling fork and by said feeler to move said transfer box from non-receiving to receiving position.

91. A weft replenishing loom having at one side thereof, a transfer box to hold the new shuttle and to receive an exhausted shuttle, a filling fork, a feeler for the filling in the running shuttle, and means controlled

by said filling fork and by said feeler to discharge the exhausted shuttle into said transfer box and to introduce the new shuttle into the loom from said transfer box.

92. A weft replenishing loom having a cycle controlling shaft, pawls to actuate said shaft, a weft feeler and a weft fork, operative connections between said weft feeler and weft fork and said pawls, and replenishing means controlled by said shaft whereby replenishment is under control of both the weft feeler and weft fork.

93. A weft replenishing loom having a shuttle to receive a coreless package of filling, and movable replenishment controlling means constructed to contact with the filling mass of maximum diameter until the filling is substantially exhausted, and whereby said feeler then makes an indicating movement.

94. A weft replenishing loom having a shuttle to receive a coreless package of filling, and movable replenishment controlling means constructed to contact with the filling mass of maximum diameter until the filling is substantially exhausted, and whereby said feeler then makes a relatively great indicating movement, and replenishing means with which said replenishment controlling means co-operates.

95. A weft replenishing loom having means to discharge the running shuttle directly from and at one end of the lay, whereby said shuttle is discharged at that side of the loom where its discharging movement begins, said loom having means to insert another shuttle by moving it directly from said support across the loom to the opposite end of the lay.

96. A weft replenishing loom having means to discharge the running shuttle from and at one end of the lay upon the forward movement of said lay after passing the dagger and to insert another shuttle by moving it from said end of the lay across the loom to the opposite end of the lay.

97. A weft replenishing loom having means to discharge the running shuttle from one end of the lay through the mouth of the box at said end and to insert another shuttle at the opposite end of the lay through the mouth of the box at said opposite end.

98. A weft replenishing loom having means to discharge the running shuttle from one end of the lay through the mouth of the box at said end upon the forward movement of the lay after passing the dagger, and to insert another shuttle at the opposite end of the lay through the mouth of the box at said opposite end.

99. A weft replenishing loom having means to discharge the running shuttle in making a transfer longitudinally, through the running shuttle mouth of its box, and directly at that side of the loom whereat the said mouth of the said shuttle box is located,

and weft replenishing means at that same side of the shuttle whereat said mouth of said shuttle box is located, whereby the running shuttle is discharged at the same side of the loom where replenishment occurs and 70 without crossing the loom.

100. A weft replenishing loom having means to discharge the running shuttle from the mouth of its box and over the cloth or warp in the loom in making a transfer. 75

101. A weft replenishing loom having means to discharge the running shuttle over the cloth or warp of the loom near the forward end of the lay stroke in making a transfer. 80

102. A weft replenishing loom having means to feel for the filling in the running shuttle, and means operatively connected therewith to discharge said shuttle through the mouth of its box after the lay passes the 35 dagger going forward.

103. A weft replenishing loom having picker sticks and means to discharge the running shuttle from the mouth of its box after the lay passes the dagger going forward, 90 said means including supplemental means acting on one of said picker sticks.

104. A weft replenishing loom having a shuttle supply box for holding a refilled shuttle located on the opposite side of the 95 loom from the lay shuttle box to be supplied therefrom, sending means connected with said shuttle supply box, means to impart replenishing movement to said shuttle supply box, and means to time said sending means 100 whereby said refilled shuttle will co-act with the vibrating lay box in such a way as to enter thereinto.

105. A weft replenishing loom having a shuttle supply box for holding a refilled 105 shuttle located on the opposite side of the loom from the lay shuttle box to be supplied therefrom, sending means connected with said shuttle supply box, means to impart replenishing movement to said shuttle 110 supply box, means to time said sending means whereby said refilled shuttle will co-act with the vibrating lay box in such a way as to enter thereinto, and means connected with said opposite lay box to eject the empty 115 shuttle therefrom.

106. A weft replenishing loom having means to insert a refilled shuttle over the material being woven in the loom and through the mouth of one of the shuttle 120 boxes.

107. In a weft replenishing loom, means to insert a replenishing shuttle diagonally over the fabric being woven into operative 125 position.

108. A weft replenishing loom having means to insert a refilled shuttle across and over the fabric being woven.

109. A weft replenishing loom having at one side thereof a transfer box for a new 130

- shuttle, and means to impart sliding and rocking movement to said transfer box, said transfer box having a shelf to receive the exhausted shuttle.
- 5 110. A weft replenishing loom having means to insert a fresh shuttle by movement across the loom at an angle to the surface of the reed of the loom.
111. A weft replenishing loom having at 10 one side thereof, a transfer box, means to move said box into a substantially horizontal position at an angle to the surface of the reed of the loom, and means to discharge the shuttle from said box.
- 15 112. A loom having a shuttle adapted to carry a coreless package, a feeler adapted to function by moving past the receding edge of said package, and means controlled by said feeler to effect replenishment.
- 20 113. A loom having a shuttle adapted to be supplied with a conically wound coreless package, a feeler adapted to function by moving past the receding concaved end of said package, and means controlled by said 25 feeler to effect replenishment.
114. A loom having a shuttle adapted to be supplied with a coreless package, a feeler external to said shuttle adapted periodically to contact with the surface of said shuttle, 30 and to function by moving past the receding edge of said package, and means controlled by said feeler to effect replenishment.
115. A loom having a shuttle adapted to be supplied with a conically wound coreless 35 package, a feeler external to said shuttle adapted periodically to contact with said package and to function by moving past the receding concaved end of said package, and means controlled by said feeler to effect replenishment.
- 40 116. A weft replenishing loom having a lay, a shuttle shaped to use a coreless package, the cavity in said shuttle being shaped snugly to hold in substantially its original 45 position until replenishment the last end to be used of said coreless package, a feeler adapted to act directly on the original surface of said last end of said coreless package, and means connected with said feeler to effect 50 replenishment.
117. A weft replenishing loom having a lay, a shuttle adapted to use a coreless package, the cavity in said shuttle being shaped snugly to hold in substantially its original 55 position until replenishment the last end to be used of said coreless package, a feeler adapted periodically to contact directly on the original surface of said last end of said coreless package, and means connected with 60 said feeler to effect replenishment.
118. A weft replenishing loom having a shuttle adapted to support a coreless weft package, means external to said package to prevent displacement of the unwithdrawn 65 portion of said package in the normal weav-
- ing operation, and co-acting means dependent in action upon the depletion of said coreless weft package to effect weft replenishment when the non-displaced remaining portion of the filling package has been sufficiently reduced to cause replenishment.
119. A loom provided with a shuttle adapted to carry a coreless weft package, means exterior to the said package constantly to prevent displacement of the unused portion of said package in the normal weaving operation, and co-acting means initiated in functioning by the still unused but positioned portion of said package and adapted upon substantial exhaustion to inaugurate replenishment.
120. A loom provided with a shuttle adapted to carry a coreless weft package, means exterior to said package constantly to prevent displacement of the unused portion of said package in the normal weaving operation, and co-acting means initiated in functioning by the still unused but positioned portion of said package and adapted to contact directly with said weft package, and connections from said means to affect the running conditions of the loom.
121. A weft replenishing loom having a shuttle to receive a coreless package of filling wound in nested cones, means to feel for the receding edge of the said package as filling is drawn from said package, and means operatively associated with said feeler means to effect replenishment when said feeler means finds said receding edge.
122. A weft replenishing loom having a shuttle to receive a coreless package of filling wound in nested cores, means to prevent displacement of the still unused portion of said package, means to feel for the receding edge of said package as the filling is withdrawn therefrom, and means operatively associated with said feeler means to effect replenishment when said feeler means finds said receding edge.
123. A weft replenishing loom having a shuttle to receive a coreless package of filling wound in nested cones and tightly fitting the weft receiving cavity of the shuttle, means to prevent displacement of the still unused portion of the package as the weft is withdrawn therefrom, and feeler means to contact with the filling adjacent to the tightly fitting tapered end of the package, and thereby to effect replenishment while the tip end portion of said package is still held from displacement in said shuttle cavity.
124. A weft replenishing loom having means to insert a refilled shuttle directly through the running shuttle mouth of one of the shuttle boxes in making the transfer, and means to effect the discharge of the exhausted shuttle in the direction of the longitudinal axis of said shuttle, directly from

- and at the side of the loom opposite the said running shuttle mouth, whereby the said discharged shuttle in its discharging movement is confined to one side only of the loom.
125. A weft replenishing loom having means to discharge the running shuttle in the direction of its longitudinal axis directly from and at one end of the lay, whereby the shuttle in its discharging movement is confined wholly to one side of the loom, said loom having means to insert another shuttle by moving it from said end of the lay across the loom to the opposite end of the lay.
126. A weft replenishing loom having a shuttle to receive a coreless package of filling wound in layers, means to feel inwardly past the exposed base of a layer of said package when the filling is substantially exhausted to present such exposed base to said feeling means, and means initiated in action by such inward movement past the exposed base.
127. A weft replenishing loom having a shuttle to receive a coreless package of filling, means externally to said package to prevent displacement of the still unused portion of the filling package, means governed by said coreless package to supply new filling to the loom when said coreless package has become substantially exhausted, and cooperating actuating means positioned to enter substantially past the wall of the shuttle only when said filling package has become substantially exhausted.
128. A weft replenishing loom having a shuttle to receive a coreless package of filling, means external to said package to hold it in substantially its original position as it diminishes in use, means wholly external to the shuttle to move inwardly past the base of a layer of said shuttle, and means initiated in action by said movement past the base.
129. A weft replenishing loom having a shuttle to receive a coreless package of filling, means external to said package to hold it in substantially its original position as it diminishes in use, a feeler adapted to enter past the outer surface of the wall of the shuttle and actuated by inward movement past the inner surface of the wall of the shuttle, and means initiated in action by said inward movement.
130. A weft replenishing loom having a shuttle to receive a coreless package of filling, means external to said package to hold it in substantially its original position as it diminishes in use, a feeler wholly external to the shuttle and actuated by inward movement past the outer surface of the package, and means initiated in action by said inward movement.
131. A weft replenishing loom having a feeler to feel for the filling in the shuttle, a feeler rod 61 distinct from but operatively connected to said feeler, means to move said feeler rod axially upon substantial exhaustion of the filling and consequent inward movement of said feeler, ratchet and pawl means initiated in action by said axial movement of the feeler rod, and weft replenishing means operated by said ratchet and pawl means.
132. A weft replenishing loom having a feeler rod 61, a pivotally mounted feeler adapted to rock into the shuttle in its indicating movement, pivotal connections between said feeler and said rod 61, means to move said rod 61 downward, and means whereby said downward movement of the feeler rod 61 causes the feeler to feel for the filling.
133. A weft replenishing loom having a shuttle to receive a package of filling, a feeler adapted to feel for the basal edge at the inner surface of the wall of the shuttle and upon inward movement when said edge is felt to function in the replenishing action and replenishing means initiated in action by said inward movement.
134. A weft replenishing loom having a shuttle adapted to carry a coreless weft package, a feeler for the edge portion of said weft package, means to cause forceful engagement of said feeler and said package, and means whereby said feeler is caused to function when it overcomes the resistance of said edge portion.
135. A weft replenishing loom having a shuttle adapted to carry a coreless weft package, a feeler for the edge portion of said weft package, means to cause forceful engagement of said feeler and said package, and means whereby said feeler is caused to function when said means to cause said forceful engagement is no longer equaled by the resistance presented by said package.
136. A weft replenishing loom having a shuttle adapted to carry a coreless weft package, a feeler for the edge portion of said weft package, means to cause forceful engagement of said feeler and said package, means to maintain the residual portion of the weft package in position when the feeler functions, and means whereby said feeler is caused to function when said means to cause said forceful engagement is no longer equaled by the resistance presented by the positioned, residual portion of said package.
137. In a weft replenishing loom in combination, a feeler, a pawl, a pawl actuated cycle controlling mechanism, a transfer mechanism for replenishing the filling, and connecting means movably connecting the feeler and the pawl whereby the functioning of the feeler will act through the cycle controlling mechanism and control said transfer mechanism.
138. In a weft replenishing loom, a weft

- feeler, a transfer mechanism, a pawl, and axially movable rod connecting the feeler and pawl, and a pawl actuated cycle mechanism operatively associated therewith, whereby 5 the time of the motion or motions of the transfer action may be controlled thereby.
139. In a weft replenishing loom, a weft feeler and a transfer mechanism for replenishing weft, and intermediary controlling 10 mechanism consisting of a pawl actuated, one revolution, shaft having one or more cams mounted thereon to control the functioning of said transfer mechanism, and a rod movable up and down and operatively 15 connecting the weft feeler and the intermediary controlling mechanism.
140. A weft replenishing loom having means to replenish weft without stopping the loom, said means including a weft feeler, 20 a cycle controlling mechanism and a weft replenishing mechanism, said cycle controlling mechanism consisting of a shaft and a ratchet mounted thereon, said ratchet having a widely spaced tooth and a pawl co-operating 25 with said ratchet.
141. A weft replenishing loom having a weft feeler and cycle controlling mechanism and a weft replenishing mechanism, said cycle controlling mechanism consisting of a 30 shaft and cam rigidly mounted thereon, a ratchet also rigidly mounted thereon and having a widely spaced tooth, an acting pawl for said ratchet not normally reaching said tooth, and a starting pawl operatively connected with said weft feeler, whereby said 35 ratchet is caused to be turned to a position where said widely spaced tooth is brought within the reach of the said acting pawl.
142. A weft replenishing loom having means to replenish weft without stopping the loom, said means including a weft feeler, a weft replenishing mechanism, a cycle controlling mechanism having a shaft, one or more functioning formations thereon, a 45 ratchet on said shaft having a widely spaced tooth, a pawl not normally reaching said ratchet, and means operatively associated with said weft feeler to bring said widely spaced tooth within reach of said pawl.
143. A weft replenishing loom having a support for a spare shuttle at one side of the loom, means to pick that spare shuttle from its support across the loom at an inclination to the face of the reed, thereby bringing said 50 spare shuttle into play, and means to discharge the exhausted shuttle off the lay from the shuttle box at that side of the loom where the spare shuttle is supported.
144. A weft replenishing loom having a 55 shuttle cavity, a coreless package of filling snugly fitting said cavity and thereby held from displacement even when approaching exhaustion, and means periodically to enter said shuttle and to feel for and to contact with the original surface of the coreless pack-
- age of filling in said cavity and through such contact with said original surface to effect replenishment.
145. A weft replenishing loom having a pivoted feeler, a feeler rod 61 pivotally connected to said feeler, a pawl 71 controlled by said rod 61, a ratchet 76 controlled by said pawl, a cam 80 controlled by said ratchet, and a pawl 84 controlled by said cam. 70
146. A loom provided with a running shuttle having a cavity to receive a package, feeler means mounted wholly isolated from the shuttle and adapted in its indicating movement to move inward past an exposed basal portion of a layer of said package, and 75 means initiated in action by the substantial exhaustion of said package and governed by the said movement of said feeler means to discharge the running shuttle at one side of the loom and to introduce a new shuttle 80 momentarily thereafter into the shuttle box at the other side of the loom.
147. A weft replenishing loom having means to discharge a running shuttle over the material being woven and through the 85 running shuttle mouth of its box in making the transfer.
148. A weft replenishing loom having means to discharge the running shuttle across the loom over the material being 90 woven and through the running shuttle mouth of its box in making the transfer.
149. A weft replenishing loom having means to discharge the running shuttle in making the transfer from the mouth of its 95 box across the loom and exterior to the material being woven.
150. A weft replenishing loom having a shuttle provided with a cavity to receive a coreless package of filling wound in nested 100 cones and tightly filling said cavity, exterior means to prevent displacement of the still unused portion of said package during the weaving operation, feeler means exterior to the shuttle periodically to contact with the filling package, means to restrain said 105 feeler means from entering the cavity of the shuttle until replenishment indication, and provisions whereby weft replenishment is effected by entering movement of said feeler 110 means into the shuttle cavity when a sufficient portion of the filling package is withdrawn.
151. A weft replenishing loom having a shuttle adapted to carry a weft package, a 115 feeler for the edge portion of said package, means to cause forceful engagement of said feeler and said package, and means whereby said feeler is caused to function when it overcomes the resistance of said edge por- 120
152. In a weft replenishing loom, means to insert a replenishing shuttle diagonally across the loom into operative position but wholly exteriorly to the fabric being woven. 125

153. A weft replenishing loom of the type which replenishes by transferring shuttles having a lay provided with a shuttle receptacle, and shuttle replenishing means including means to move the replenishing shuttle across the loom in an inclined direction so related to the linear velocity that the backward and forward component of said linear velocity will approximate the backward and forward velocity of the said shuttle receptacle at the instant of the entrance of said shuttle into said receptacle, thereby making the entrance of said receptacle thereinto as shockless as practicable.
154. Weft replenishing loom of the type which replenishes by transferring shuttles provided with a lay having a shuttle box secured thereto, and shuttle replenishing mechanism including means to throw the entering shuttle across the loom in an inclined direction having such relation to the linear velocity of the entering shuttle that the backward and forward component of said linear velocity will approximate the backward and forward velocity of the said shuttle box at the instant of the entrance of said shuttle into said box, thereby making said entrance as shockless as practicable.
155. A loom provided with a shuttle adapted to carry a coreless weft package, said shuttle having means to hold the weft package exteriorly and in normal weaving position in the shuttle until feeler indication occurs, a feeler mounted externally of the shuttle and adapted to contact with the last end of the said coreless package, and means controlled by contact of the feeler with said normally positioned last end of the weft package to effect replenishment.
156. A loom provided with a shuttle, having means to hold exteriorly a coreless weft package, a feeler adapted to contact with the last end of the said coreless package, and means whereby the last end of the said package while in normal weaving position in the shuttle acts by engagement with said feeler to effect replenishment.
157. A loom provided with a shuttle adapted to receive a coreless weft package wound in nested conical layers, means to hold the weft package exteriorly and to maintain the remaining unused portion of said package in substantially its initial position in said shuttle until feeler indication occurs, a feeler adapted to co-act with said positioned package, and means controlled by said feeler to effect replenishment.
158. A loom provided with a shuttle adapted to hold a weft package by contact with its exterior surface, means to maintain the unused portion of said package in substantially its initial position in said shuttle until the time of feeler indication, a feeler adapted to co-act with said positioned package, and means controlled by said package to effect replenishment.
159. A loom provided with a shuttle having means to hold exteriorly and position a weft package, a feeler mechanism adapted to co-act with said positioned weft package, means to hold in substantially its initial position in said shuttle that portion of the original surface of said weft package which said feeler mechanism acts upon until the time of feeler indication, and means controlled by said feeler to effect replenishment.
160. A loom provided with a shuttle adapted to hold a coreless weft package, a weft package wound in nested cones, means to hold said package externally including the last remaining end to be used in substantially its initial position in said shuttle, a feeler designed to act at the convexed end of said positioned package, and means controlled by said feeler to effect replenishment.
161. A loom provided with a shuttle adapted to hold a coreless package, a feeler mechanism adapted to co-act with the original surface of said positioned weft package, means to hold in substantially its initial position in said package that original portion of the surface of said weft package which said feeler mechanism acts upon at the time of feeler indication, and means controlled by said feeler to effect replenishment.
162. A weft replenishing loom having means to discharge the running shuttle in making a transfer through the running shuttle mouth of its box and directly at that side of the loom whereat the said mouth of the said shuttle box is located, and whereat said shuttle is located when replenishing movement occurs, and weft replenishing means at the same side of the loom where indication occurs and whereat the running shuttle is discharged, and whereby the running shuttle is discharged through said mouth of the shuttle box without crossing the loom.

In testimony whereof, I have signed my name to this specification.

LOUIS S. BURBANK.
